SKIP LOADING MECHANISM

Mahlon E. First, Cleveland, Ohio, assignor to The
C. O. Bartlett & Snow Company, Cleveland,
Ohio, a corporation of Ohio

Application July 31, 1940, Serial No. 348,762

14 Claims. (Cl. 214—125)

This invention relates to skip-loading mechanism, and more particularly, to an improved arrangement of mechanism by which movement of a gate closure member or chute, through which materials are fed to a skip when in charging position, is automatically controlled by movement of the skip to and from charging position.

The invention is particularly designed for automatically operated skip-loading mechanism of the type wherein the skip is mounted for rolling movement on a steeply inclined track to and from charging position relative to the charging gate. Such apparatus is commonly provided with a chute or gate closure member which is pivotally mounted for movement between closed and open positions to control movement of the materials into the skip. It is customary to provide mechanism for causing the gate to move automatically to open position as the skip or bucket approaches charging position and for moving the gate to closed position after the bucket has received a supply of materials.

In controlling the movement of the gate closure member between its open and closed positions, the mechanism commonly in use is usually provided with a counterweight for holding the gate in closed position and a latching device for holding the gate in open position. An operating arm, which is adapted to be struck by the skip as it moves toward charging position, is provided to move the gate closure member to open position against the action of the counterweight. Due to the weight of the parts involved, there is a relatively large amount of inertia tending to resist movement of the operating arm and gate closure member under the influence of the moving skip. Accordingly, when the rapidly moving skip strikes the operating arm, the mechanism is jarred severely and subjected to extremely heavy shocks by the impact of the rapidly moving bucket, thereby causing considerable wear and breakage of parts of the mechanism.

In order to eliminate the difficulties incident to the shock and jarring encountered in the use of such apparatus, this invention contemplates the provision of a novel form of control mechanism by which the action or operation of the gate in moving to and from closed position will be accomplished in a smooth and gentle manner. The mechanism employed for this purpose involves the use of camming mechanism by which the opening and closing movement of the gate is directly controlled by movement of the bucket without imparting a jarring movement to the gate. In connection with the mechanism

employed for controlling the movement of the gate by the movement of the bucket, there is also employed a novel form of locking mechanism which is operable to lock the gate upon movement thereof to closed position, and to release the gate for movement to open position upon movement of the skip toward charging position.

With the foregoing in view, one of the principal objects of this invention is to provide a novel form of control mechanism for a skip bucket and a discharge gate closure member by which movement of the gate closure member between open and closed positions will be controlled by movement of the skip to and from its charging position.

A further object is to provide a novel form of locking mechanism automatically releasable solely by movement of the gate upon movement of the skip toward charging position without the necessity of employing any positively actuated devices to effect a release of the locking mechanism to permit movement of the gate to open position.

A further object is to provide mechanism for effecting movement of the gate out of a normal closed position to a second closed position, together with a novel form of locking mechanism which is automatically releasable to permit movement of the gate to open position upon movement of the gate to the second closed position by the skip bucket.

To the accomplishment of the foregoing and related ends, said invention, then, consists of the means hereinafter fully described and particularly pointed out in the claims. The annexed drawings and the following description set forth in detail certain mechanism embodying the invention, such disclosed means constituting, however, but one of various mechanical forms in which the principle of the invention may be used.

In the drawings there is shown a preferred embodiment of the invention. In this showing:

Fig. 1 is a side elevational view showing the position of the parts with the skip bucket in its charging position;

Fig. 2 is a side elevational view of a part of the apparatus shown in Fig. 1, and showing the position of the gate when locked in its closed position;

Fig. 3 is a broken-away, side elevational view of a part of the apparatus shown in Fig. 1, and showing the position of the gate relative to the control parts just prior to movement into locked position;

Fig. 4 is a view similar to Fig. 3, showing the

position of the parts after movement of the gate into locked position;

Fig. 5 is a sectional view taken substantially on the line 5—5 of Fig. 3;

Fig. 6 is a sectional view taken substantially on the line 6—6 of Fig. 3; and

Fig. 7 is a sectional view taken substantially on the line 7—7 of Fig. 4, parts having been illustrated as broken away centrally of this showing.

Referring to the drawings, the letter A designates a material supply bin provided with a hopper discharge B, having a gate closure member C pivotally mounted thereon for movement between an open position, as shown in Fig. 1, to a closed position, as shown in Fig. 2. The gate C illustrated is of the type known as an undercut gate and when in opened position, is adapted to supply material from the hopper B to a skip or bucket D, mounted for movement to and from charging positions on a track E. The operation and construction of the foregoing parts are well-known, this invention being limited to the control mechanism, to be described, mounted on the parts referred to, and by which movement of the gate C between its open and closed positions is controlled by movement of the bucket D to and from its charging position.

To control the movement of the gate C by movement of the skip D, an angle member 1 is secured to a side of the gate C, the angle member 1 having a flange 2 projecting laterally outwardly therefrom to provide a camming surface 3 for engagement with a roller 4, as best shown in Fig. 6. The flange 2 is formed in three portions angularly inclined with respect to each other in order to provide separate camming surfaces 3a, 3b and 3c, as best shown in Figs. 3 and 4, for a purpose to be described. The roller 4 is rotatably mounted in brackets 5 rigidly secured to a side 6 of the skip D.

Locking mechanism, indicated as a whole by the numeral 7, is provided for locking the gate C in closed position. The locking mechanism 7, as best shown in Figs. 3, 4 and 5, comprises a detent or hook member 8 having a notch 9 for the reception of a locking part or roller 10, carried by the gate C. The hook member 8 is pivotally mounted on a shaft 11 carried by angle-iron brackets 12 and 13, the angle-iron 12 constituting a supporting member rigidly secured to the hopper B and the angle-iron bracket 13 being carried by an angle bracket 14 rigidly secured to the upper flange of the supporting angle bracket 12.

An operating lever 15, having a roller 16 at the outer end thereof, for the hook member 8, is rigidly connected to the detent or hook member 8 for rotation therewith by means of a sleeve 17 having a welded connection with both the lever 15 and the hook member 8. As best shown in Fig. 3, most of the weight of the pivotal parts, including the operating lever 15 and detent 8, is to the right of the pin 11, providing a gravitational bias tending to move these parts in a clockwise direction to their unlocking position shown in Fig. 3. The hook 8 is provided with an abutment 18 engageable with the under-surface 19 provided by a laterally extending flange of the support 12 to limit movement of the detent 8 and lever 15 under their gravitational bias.

In connection with the gravitational bias of the parts 8 and 15, it will also be noted that the gate C, and therefore the locking pin or roller 10, has a gravitational bias from its closed and locked position to its open position, due to the pivotal

mounting of the gate C on the hopper B. Upon movement of the locking part 10 into the notch 9, as shown in Fig. 4, these parts will interlockably engage with each other to prevent movement of the gate C and detent 8, under influence of their gravitational biases, respectively, to open and unlock positions.

In order to effect movement of the lever 15 and thereby the hook member 8, against their gravitational bias to locking position, an actuating member 20 is connected to the side of the skip D. The actuating member 20 is provided with an upwardly projecting flange 21 having a surface 21a engageable with the roller 16, to effect a control action on the lever 15 and hook member 8 in a manner to be described.

Although the control parts have been described as being positioned respectively on one side only of the bucket D and gate C, it will be understood that such parts could advantageously be arranged centrally of the gate C, or alternatively, two sets of such control parts could be respectively arranged on opposite sides of the gate C and bucket D. The sectional view shown in Fig. 7 illustrates the construction wherein the control parts are thus provided on both sides of the gate C and bucket D.

The operation of the apparatus is as follows:

With the locking lug positioned in the notch 9, as shown in Fig. 4, the gate C will be held in its closed position against movement under its gravitational bias, to open position. As pointed out heretofore, the interlocking engagement of the lug 10 with the hook member 8 will be operative to prevent movement of the pivotally movable parts 15 and 8 under their gravitational bias to unlocking position. Upon downward movement of the skip D toward charging position, the first action that will take place will be the movement of the roller 4 into engagement with the camming surface 3a. As movement of the skip D continues, the roller 4 will cam the gate C upward from its normal closed and locked position, in a direction away from its open position to a position, shown in Fig. 3, which will be referred to as a "second closed position," this camming movement of the gate C by engagement of the roller 4 with the cam surface 3a being operative to move the locking roller 10 out of the notch 9 on the detent 8. The gate C reaches the second closed position upon movement of the roller 4 into engagement with the camming surface 3b, which surface, with the gate C in its second closed position, is parallel to the travel of the bucket D. The gate C will be stationary during the time that the roller 4 is in engagement with the camming surface 3b, and the parts are so positioned that the roller 16 will move out of engagement with the surface 21a while the gate C is in its second closed position, to permit the detent 8 and operating lever 15 to be moved by their gravitational bias to unlocking position, as shown in Fig. 3.

Thereafter, upon further continued downward movement of the skip D, the roller 4 will move into engagement with the camming surface 3c, which will permit the gate C to move downwardly under its gravitational bias to open position. As shown in Fig. 3, it should be noted that the cam surface 3c is substantially parallel to the direction of travel of the roller 4 as the roller 4 moves into engagement with this surface. The gravitational bias of the gate C will maintain the camming surface 3c in engagement with the roller 4 and the speed of opening movement of the gate C will thereby be con-

trolled by the speed of the bucket D. Due to the position of the camming surface 3c with respect to the direction of travel of the roller 4 and the pivotal mounting of the gate C, it will be apparent that initial downward movement of the gate C from its closed position will be relatively slow with respect to the movement of the bucket D at a predetermined point in its path of movement toward charging position. Accordingly, as the bucket D moves toward or away from this predetermined point, it will be apparent that the rate of pivotal movement of the gate C will progressively increase or decrease as the bucket D moves away from or toward such predetermined point.

After the bucket D has been filled with materials, the gate C will be moved to its closed position upon movement of the bucket D away from its charging position by engagement of the roller 4 with the camming surface 3c. When the roller 4 moves onto the camming surface 3b, the gate C and roller 10 will be returned to their so-called "second closed position." As this position is reached, the upper end of the flange 21 will strike the roller 16 and move the lever 15 and detent 8 against its gravitational bias from the position shown in Fig. 3, to a position with the notch 9 underneath the locking roller 10. The roller 16 will be maintained in this position, or its locking position, by engagement with the surface 21a until the roller 4 moves into engagement with the camming surface 3a to permit a downward pivotal movement of the gate C from its "second closed position" under the influence of its gravitational bias toward open position, to its normal closed or locked position with the roller 10 in interlocking engagement with the notch 9 of the detent 8. Thereafter, the roller 16 will move out of engagement with the surface 21a and the roller 4 will move out of engagement with the camming surface 3a, and the detent 8 and the gate C will be held from movement under the influence of their respective gravitational biases until the subsequent return of the skip D to charging position to effect subsequent actuation of the control mechanism, as before stated.

When the skip D ascends, and after the roller 4 thereon by engagement with the cooperating camming surfaces on the gate has moved the latter to the "second closed position," further ascending movement of the skip D will, as explained, result in engagement by the member 21 with the roller 16 on the arm 15 of the detent 8, moving the detent in a counter-clockwise direction as viewed in Fig. 4. The parts are so proportioned and positioned relatively to each other that, as the roller 16 rides downwardly on the surface 21a, simultaneous with upward movement of the roller 4 over the camming surface 3a, the gate C will be permitted to rotate in a counter-clockwise direction, as viewed in Fig. 4, and the pin 10 dropped into the notch 9 of the detent 8. The parts are so proportioned and positioned relatively to each other that the pin 10, in thus dropping into the notch 9, first strikes the right-hand face of such notch 9 viewed in Fig. 4. The weight of the gate, causing the pin 10 to settle into the bottom of the notch 9, will cause a slight counter-clockwise movement of the detent 8 from the position in which such detent is maintained by the surface 21a. In this way, the arm 15 and its contacting roller 16 will actually be lifted out of engagement with the face

21a of the member 21 by the gate as it settles to its closed position.

When the skip next descends, the roller 16 will not be engaged by the surface 21a until after the roller 4 has begun movement of the gate C to its "second closed position." This expedient further eliminates undesirable shock to the apparatus in the operation of the latching device.

At this point it may be observed that the camming surface on the gate closure member comprising the sections 3a, 3b, and 3c may be modified from that shown and described above and still have the apparatus operate in accordance with the principles of my invention. The cam surface 3a being, when the gate closure member is in its locked position, inclined to the line of movement of the skip, is, of course, relied upon to move the gate closure member into its "second closed position" so that the roller 10 will be moved out of engagement with the hook 9 in order that the latter may, under its gravitational bias, swing to the unlocked position, and to permit movement of the detent 8 into its locking position when the skip travels upwardly. The camming surface 3b has been shown as arranged substantially parallel to the line of movement of the skip, while the gate is in its "second closed position," so that the gate is held in the latter position by the roller 4 for a sufficient length of time during the descent of the skip to permit the detent 8 to move from the locked into the unlocked position, and in the ascent of the skip to permit the detent 8 to move from the unlocked position into the locked position. It is, of course, not necessary that the gate C be stationary during this interval, and it is, therefore, possible to construct the camming surfaces with two angularly related components, such as 3a and 3c, without an intermediate component, such as 3b, provided the two camming surfaces are so proportioned that the gate C will be moved under the influence of the roller 4 on the skip, in a counter-clockwise direction as viewed in Fig. 4, for a distance sufficient to permit movement of the detent 8 in a clockwise direction, as viewed in said figure, from the locking position to the unlocking position when the skip descends, and in a counter-clockwise direction from the unlocking position to the locking position when the skip ascends.

From the foregoing, it will be apparent that that there is provided a novel form of control mechanism comprising the camming member 3 and the roller 4 for easily and positively controlling the movement of the gate C between its open and closed positions without shocks or jars, as is the case with control mechanism now commonly in use.

It will also be apparent that the manner in which the locking detent is automatically moved under its gravitational bias to unlocking position contributes to the ease of operation in that this detent is released of all weight before moving to its unlocking position.

It will additionally be apparent that the manner in which the gate C is operated to permit movement of the locking detent 8 provides a co-operation of the respective gravitational biases of the gate C and locking detent 8 toward effecting the desired results.

In connection with the use of the word "skip" to describe the device D into which materials are charged, it is to be understood that this word is used in its generic sense and is intended to cover all types of containers or receptacles which

are movable to and from a charging position relative to a charging device. It will also be understood that the present invention is equally well adapted for use in constructions wherein the skip or receptacle D is mounted for movement in a truly vertical as well as a horizontal plane instead of in an inclined plane, as shown in the drawings.

Other modes of applying the principle of the invention may be employed, change being made as regards the details described, provided the features stated in any of the following claims, or the equivalent of such, be employed.

I therefore particularly point out and distinctly claim as my invention:

1. Apparatus of the character described comprising, in combination, a gate closure member mounted for movement between open and closed positions and having a bias toward its open position, a detent movable between locking and unlocking positions and having a bias toward its unlocking position, a skip movable on fixed guides, an element mounted on said skip operative responsive to upward movement of said skip to engage said gate when in open position and to lift it to closed position, and a locking part mounted on said gate adapted to interlockably engage with said detent when said detent is in locking position and said gate is in closed position to hold said detent and gate in such positions against their respective biases.

2. Apparatus of the character described comprising, in combination, material charging mechanism including a gate closure member mounted for movement between open and closed positions and having a bias towards its open position, a detent movable between locking and unlocking positions and having a bias toward its unlocking position, a skip movable to and from a charging position relative to said gate, an element on said skip operative responsive to upward movement of said skip to engage said gate when in open position and to lift it to closed position, a locking part mounted on said gate adapted to interlockably engage with said detent when said detent is in locking position and said gate is in closed position to hold said detent and gate in such positions against their respective biases, and means operable upon movement of said skip to a predetermined point in its path of movement toward charging position to effect movement of said locking part out of engagement with said detent to permit movement thereof under its bias to unlocking position.

3. Apparatus as claimed in claim 2 together with operating means including a part operable to effect movement of said detent to locking position against its bias, upon movement of said gate to closed position.

4. Apparatus of the character described comprising, in combination, material charging mechanism including a gate closure member movable between open and closed positions, a skip movable to and from a charging position relative to said gate, a detent mounted for movement between locking and unlocking positions and having a bias toward its unlocking position, a locking part mounted on said gate adapted to interlockably engage with said detent when said gate is in a normal closed position and said detent is in its locking position, and means operable upon movement of said skip toward charging position to effect movement of said gate from its normal closed position to a second closed position, said locking part being movable with said gate out of

interlocking engagement with said detent to release said detent for movement under its bias to unlocking position upon movement of said gate to said second closed position.

5. Apparatus of the character described comprising, in combination, material charging mechanism including a gate closure member mounted for pivotal movement between open and closed positions, said gate having a bias for movement from closed to open position, a detent movable between locking and unlocking positions and having a bias toward its unlocking position, and a locking part mounted on said gate adapted to interlockably engage with said detent when said detent is in locking position and said gate is in closed position to hold said detent and gate in such positions against their respective biases, a skip movable to and from a charging position relative to said gate, cooperating camming devices carried by said skip and gate operable upon movement of said skip to a predetermined point in the path of its movement toward charging position to effect movement of said gate against its bias out of closed position to a second position with said locking part out of engagement with said detent to permit movement of said detent under its bias to unlocking position, said camming devices being operable upon continued movement toward charging position to permit movement of said gate under its bias to open position, said camming devices being operable upon movement of said skip away from charging position to effect a return of said gate against its bias to said second position, and operating means including a part carried by said skip for returning said detent to locking position substantially upon movement of said gate from open position to said second position, said camming devices being operative upon further movement of said skip from charging position to permit a further movement of said gate to closed position under its bias to effect movement of said locking part into interlocking engagement with said detent.

6. Apparatus of the character described comprising in combination, material charging mechanism including a gate closure member mounted for pivotal movement between open and closed positions and having a bias toward open position, a detent movable between locking and unlocking positions and having a bias toward its unlocking position, a locking part carried by said gate and adapted to interlock with said detent when in its locking position and said gate is in its closed position, a skip movable to and from a charging position relative to said gate, a member having a camming surface carried by said gate, a cam mounted on said skip engageable with said camming surface upon movement of said skip to a predetermined point in the path of its movement toward charging position to cam said gate from a normal closed position to a second position with said locking part out of engagement with said detent to permit movement of said detent under its bias to unlocking position, said cam being operable upon movement of said skip away from charging position to said predetermined point to return said gate to said second position, operating devices respectively carried by said skip and detent and operable to effect movement of said detent to locking position upon movement of said gate by said skip to said second position,

said cam being operative upon further movement of said skip from charging position to permit movement of said gate under its bias from said second position to its normal closed position to return said locking part into interlocking engagement with said detent.

7. Apparatus as claimed in 6 wherein the operating device carried by said skip is operable to maintain said detent in its locking position during such time as the gate is being moved back and forth between its closed and first positions to effect movement of said locking part into and out of interlocking engagement with said detent.

8. Apparatus of the character described, in combination, a movably supported gate, a skip mounted for movement relative to said gate, a movably supported latch arranged for latching engagement with a portion of said gate, said latch being biased for movement to unlatching position and provided with an actuating part disposed in the path of movement of at least a portion of said skip while said latch is in unlatching position and out the path of such portion while said latch is in the latching position, and cooperating means on said skip and gate effective upon relative movement between the same while the latter is in latched position to move the gate sufficiently to permit said latch to move to unlatching position.

9. Apparatus of the character described, in combination, a movably supported gate, a skip mounted for movement relative to said gate, a movably supported latch arranged for latching engagement with a portion of said gate, said latch being biased for movement to unlatching position and provided with an actuating part disposed in the path of movement of at least a portion of said skip while said latch is in unlatching position, and cooperating means on said skip and gate effective upon relative movement between the same while the latter is in latched position to move the gate sufficiently to permit said latch to move to unlatching position.

10. Apparatus of the character described comprising, in combination, a gate closure member mounted for movement between open and closed positions and having a bias toward its open position, a detent movable between locking and unlocking positions and having a bias toward its unlocking position, a locking part mounted on said gate movable into engagement with said detent, said detent having a notch therein adapted to receive said locking part, movement of said locking part into engagement with said notch being operative to effect a movement of said detent against its bias to an interlocking position with said locking part holding said gate and said detent, respectively, in closed and locking position against their respective biases, a skip movable to and from a charging position relative to said gate, an element on said skip operative responsive to upward movement of said skip to engage said gate when in open position and to lift it to closed position.

11. Apparatus of the character described comprising, in combination, a gate closure member mounted for movement between open and closed positions and having a bias toward its open position, a detent movable between locking and unlocking positions and having a bias toward its

unlocking position, and a locking part mounted on said gate movable into engagement with said detent, said detent having a notch therein adapted to receive said locking part, means for moving said detent against its bias to a position wherein said notch is adapted to receive said detent, movement of said locking part by the bias of said gate into engagement with said notch being operative to effect a further movement of said detent against its bias to an interlocking position with said locking part holding said gate and said detent, respectively, in closed and locking position against their respective biases, a skip movable to and from a charging position relative to said gate, an element on said skip operative responsive to upward movement of said skip to engage said gate when in open position and to lift it to closed position.

12. Apparatus of the character described comprising, in combination, a movably supported gate having a bias toward open position, a skip movable to and from charging positions relative to said gate, an element on said skip operative responsive to upward movement of said skip to engage said gate when in open position and to lift it to closed position, a latch movable between locking and unlocking positions and having a bias toward its unlocking position, said gate having a part inerlockably engageable with said latch for preventing movement of said gate and latch by their respective biases, and means operable upon movement of said skip toward charging position to move said part out of interlocking engagement with said latch to release said latch for movement under its bias to unlocking position.

13. Apparatus of the character described comprising, in combination, a movably supported gate having a bias toward open position, a skip movable on fixed guides to and from charging positions relative to said gate, an element on said skip operative responsive to upward movement of said skip to engage said gate when in open position and to lift it to closed position, a latch movable between locking and unlocking positions and having a bias toward its unlocking position, said gate having a part interlockably engageable with said latch for preventing movement of said gate and latch by their respective biases, and means effective upon movement of said skip away from charging position to positively move said latch against its bias to its locking position.

14. Apparatus of the character described, in combination, a movably supported gate, a skip mounted for movement relative to said gate, a movably supported latch arranged for latching engagement with a portion of said gate, said latch being biased for movement to unlatching position and provided with an actuating part disposed in the path of movement of an element carried by one of said relatively movable parts while said latch is in unlatching position and out of the path of such element while said latch is in the latching position, and cooperating means on said skip and gate effective upon relative movement between the same while the latter is in latched position to move the gate sufficiently to permit said latch to move to unlatching position.
